JOSEPH BLANCHET, OF PROVIDENCE, RHODE ISLAND, ASSIGNOR OF ONE-HALF TO LOUIS GUEDESS, OF WOONSOCKET, RHODE ISLAND.

PICKING-MOTION FOR LOOMS.

SPECIFICATION forming part of Letters Patent No. 657,726, dated September 11, 1900.

Application filed March 26, 1900. Serial No. 10,117. (No model.)

To all whom it may concern:

Be it known that I, JOSEPH BLANCHET, a citizen of the United States, residing at Providence, in the county of Providence and State of Rhode Island, have invented a new and useful Improvement in Picking-Motions for Looms, of which the following is a specification.

This invention has reference to an improvement in the picking-motion of looms; and it consists in the peculiar and novel construction whereby the picker is operated directly from the rock-shaft, as will be more fully set forth hereinafter.

15 In picking-motions as heretofore constructed the cams on the cam-shaft operate the rock-shafts on the two sides of the loom and actuate a lever on each of the rock-shafts, which lever is connected by means of a strap 20 to the picker-stick, which engages with the picker.

The main object of this invention is to simplify the construction and operation of the picking-motion by reducing the number of 25 parts as well as the weight and friction of the parts.

In carrying out my invention I lock the cam-shaft as low as possible on the sides of the loom, with the rock-shafts below the cams, 30 and I extend the lever from the rock-shaft to or nearly to the level of the picker and connect the lever with the picker by means of a flexible blade.

Figure 1 is a transverse sectional view of 35 parts of a loom, illustrating my invention. Fig. 2 is a rear view of one end of the lay of a loom, showing the connection of the lever with the picker. Fig. 3 is a detail showing the pivotal connection of the picker-strap 40 with the lever. Fig. 4 is a face view of the adjustable bearing of the rock-shaft. Fig. 5 is a detail view of the lever extending from the rock-shaft and the stop limiting the movement of the lever. Fig. 6 is a transverse sectional view of the rock-shaft, showing the 45 cam-shoe adjustably secured to the same.

In the drawings, A indicates one of the side frames of the loom; A', a strut extending from one side frame to the other; A², the lay-beam; A³, the lay-sword; A⁴, the shuttle-box; A⁵, the picker; A⁶, the cam-shaft, which is shown in Fig. 1 provided with the

ball-cams A⁷ A⁸ usually used in woolen-loom.

A⁸ in Fig. 2 indicates the picker-rod, which 55 is partly broken away to show the picker-slot A⁹ in the rear side of the shuttle-box.

The preferably square rock-shaft B is journaled at one end in the bracket B' and at the other end in the block B², which is supported 60 adjustably in the recessed plate B³ between the screws B⁴ B⁵. The cam-shoe B⁵ is preferably formed in one piece with the rectangular sleeve B⁶ and is longitudinally adjustable on the rock-shaft B, to which it is secured by the screws B⁷ B⁸. By this construction the shoe B⁵ can be adjusted to the ball-cams A⁷ by vertically raising or lowering the end of the rock-shaft supported in the block B² and by moving the shoe longitudinally 70 on the rock-shaft.

The lever C has at its lower end the sleeve C', the square hole, in which loosely fits the rock-shaft B, and is secured to the shaft by the bolts C². The bracket C³ is slotted part 75 of its length and is secured to the frame A by a bolt and may be accurately adjusted, so that the rubber or other cushion C⁴ will arrest the lever C at the desired point. The set-screw C⁵ assists in the adjustment. The strap C⁶, 80 secured at one end to the lever C, is connected to the floor-spring C⁷ in the manner usual with picker-sticks and acts to return the lever C to the positions shown in Figs. 2 and 5. The upper end of the lever C is bifurcated and 85 provided with the pivot C⁸. The frame C⁹ has one of the bearing-blocks adjustably held, so that the same may be adjusted to bear on the pivot C⁸ by means of the screw C¹⁰.

The picker is provided with the bracket- 90 plate C¹¹. The blade C¹², preferably of flexible steel, is secured to the frame C⁹ and pivotally connected to the lower part of the plate C¹¹. A number of holes in the blade C¹² permit of the adjustment of the pivotal connection of the blade with the plate C¹¹.

When in operation on a loom, the revolution of the cam-shaft brings one of the balls A⁷ in contact with the cam-shoe on one side of the loom and then the other ball A⁸ in contact with the cam-shoe on the opposite side of the loom, while the crank-shaft makes two revolutions and reciprocates the lay twice. The passing of the ball-cam over the cam-shoe

rocks the rock-shaft and moves the bifurcated end of the lever C, and with it the picker, quickly inward, throwing the shuttle from the shuttle-box across the loom. The length of 5 and the flexibility of the blade C¹² permit the lay to swing through the arc of a circle required to beat up the cloth; but at the moment when the shuttle is thrown the picker-plate is practically in line with the lever C and the shuttle 10 is readily thrown. Fig. 1 shows the relative positions of the parts at the moment the cam acts on the shoe and the shuttle is thrown from the shuttle-box.

Having thus described my invention, I 15 claim as new and desire to secure by Letters Patent—

In a picking-motion for looms, the combination with the picker A⁵ and the plate C¹¹ connected to and moving with the picker, of

the flexible blade C¹² pivotally secured to the 20 plate C¹¹, the frame C⁹ secured to the blade C¹² and having an adjustable journal-block bearing on the pivot C⁸, the lever C secured to a cam-actuated rock-bar located at the lower part of the loom-frame, the floor-spring 25 connected with the lower end of the lever C, and the stop C³ adjustably secured to a fixed part of the loom and having the cushion C⁴; whereby the motion of the cam-actuated rock-bar is transmitted at increased speed through 30 the lever C directly to the picker, as described.

In testimony whereof I have signed my name to this specification in the presence of two subscribing witnesses.

JOSEPH BLANCHET.
